UNITED STATES PATENT OFFICE.

FRED L. CAYE, OF DETROIT, MINNESOTA.

LOADING APPARATUS.

Application filed April 29, 1921. Serial No. 465,390.

To all whom it may concern:

Be it known that I, FRED L. CAYE, a citizen of the United States, residing at Detroit, in the county of Becker and State of Minnesota, have invented certain new and useful Improvements in Loading Apparatus, of which the following is a specification.

The invention appertains to improvements in loading apparatus or machines, and has for its principal object to provide for a self-propelled type of the same adapted for universal use in effecting the loading of various materials from the ground level, 15 or from points above or below the ground level as may be desired or necessary.

Another important object of the invention is to provide for a loading machine of the character mentioned, and one which is 20 capable of an excavating or digging operation, as in the forming of ditches, trenches or the like, or for the otherwise loosening up of hard packed or solidified material from piles, such as coal, gravel, manure, 25 sand and the like, in addition to the loading of the dug or loosened dirt or material directly onto the vehicles to be loaded.

With the foregoing and other objects in view, the invention resides in the certain 30 novel and useful construction and arrangement of parts as will be hereinafter more fully described, set forth in the appended claims, and illustrated in the accompanying drawings, in which:

Figure 1 is a side elevation of the preferred embodiment of the apparatus or machine,

Fig. 2 is a top plan view of the same showing the conveyor mechanism per se,

Fig. 3 is a top plan view of the wheeled truck frame with the conveyor mechanism and digging apparatus removed therefrom,

Fig. 4 is a vertical transverse section taken on the line 4—4 of Fig. 3,

Fig. 5 is a perspective view of one of the interchangeable, excavating or scraping shovels of the excavating mechanism,

Fig. 6 is a top plan view of the excavating apparatus per se,

Fig. 7 is a vertical longitudinal section taken on the line 7—7 of Fig. 6,

Fig. 8 is a vertical longitudinal section taken on the line 8—8 of Fig. 2.

Fig. 9 is a vertical transverse section taken on the line 9—9 of Fig. 6, and, 55

Fig. 10 is a vertical transverse section taken on the line 10—10 of Fig. 8.

Referring to the drawing, wherein similar characters of reference designate corresponding parts in the several views thereof, 60 the numeral 10 indicates an elongated substantially rectangular truck frame which is mounted on a front wheeled steering truck 11 and a rear wheeled driving truck 12, the steering of the front wheeled truck 11 65 being effected in any usual manner, or, as shown, by means of flexible elements or cables 13 connecting, at one of their ends, the opposite ends of the truck axle, as at 14,

and at their other ends a winding shaft 15 70 journaled transversely of the frame 10, which shaft 15 is to be rotated from one side and outwardly of the latter by means of a hand crank 16, while the rear truck 12 has

its traction wheels driven through the medium of a sprocket 17, on the axle thereof, 75 which is, in turn, driven by means of a sprocket chain 18 connecting a sprocket 19 carried on a drive shaft 20, which is journaled transversely of the truck frame 10. 80

The shaft 20 is adapted to be connected or disconnected from a driven sprocket 21, 85 loosely mounted on the same, through the medium of a clutch mechanism 22, the movable element of which is arranged to be properly manipulated from a point at the side of the truck frame 10 by means of a pivoted bell crank lever 23. The sprocket 21 is driven by means of a sprocket chain 24

from a sprocket 25 keyed on a power 90 distributing shaft 26, which is journaled in transversely spaced standards 27 rising at opposite sides of the upper faces of the longitudinally extending bars of the truck frame 10. The power distributing shaft 26

is driven through a clutch mechanism 28 95 from a sprocket 29, which, in turn, is driven by a sprocket chain 30 leading to and connecting a sprocket on the power shaft of an engine or motor 32, the clutch mechanism 100 28 being operable through the medium of a suitably pivoted lever 33 which projects to the same side of the truck frame 10, from which the steering crank 16 and the clutch lever 23 are manipulated. The engine or 105 motor 32 is suitably secured in position on

a base or bed plate 34 bolted on the upper face of the rear end of the truck frame 10.

Pivotedly mounted, as at 35, on the forward end of the truck frame 10, and at a point approximately on its transverse center, is a conveyor frame 36 which inclines upwardly of the front end of the truck frame 10 and rearwardly over a minor portion of the forward end thereof, and has journaled transversely of its opposite ends a pair of rollers 37 and 38 on which is carried an endless conveyor belt 39, the opposite sides of the conveyor frame 35 being provided with outwardly inclined plates 40 rising above the upper face of and to either side of the conveyor belt 39, whereby to prevent side discharge of the material in its passage upwardly of the latter. The upper end of the conveyor frame 36 is disposed in overlapping relation with respect to a second conveyor frame 41 which extends to a point beyond the rear end of the truck frame 10, and has journaled transversely of its opposite ends a pair of rollers 42 and 43, on which is carried an endless belt conveyor 44, the opposite sides of the frame 41 being provided with plates 45 rising above the upper face of the conveyor belt 44 to prevent the side discharge of material therefrom in its travel on the latter from the conveyor belt 39. The forward end of the conveyor frame 41 is supported from the rear end of the conveyor frame 36 by means of oppositely disposed plates or hangers 46 which are engaged at their opposite ends on the shafts of the rollers 38 and 42, while extending rearwardly from the sides of the conveyor frame 36, and connecting the opposite ends of the shaft of the roller 38 are a pair of brace bars 47 which connect the conveyor frame 41 at points beyond the transverse center thereof, as at 48. Depending from the opposite sides and inwardly of the rear upper end of the conveyor frame 36 are a pair of supporting bars 49, which are pivoted to the frame 36, as at 50, and extend downwardly at opposite sides of the truck frame 10 and have their lower ends formed to provide elongated slotways 51 engaged over the projecting ends of a shaft 52, which is journaled transversely of the truck frame 10, and racks 53, are formed at one side of the slotways 51, and arranged in mesh with pinions 54 carried on the complementary ends of the shaft 52, a hand crank 55 being secured on the projecting end of the shaft 52 for its manipulation for the raising and lowering movements of the conveyor frames 36 and 41 and from the same side of the truck frame 10 as the other of the several manually operated lever and hand cranks as hereinbefore stated. A pivoted dog 56 is cooperative with one of the pinions 54 for holding the shaft 52 from retrograde movement, after the rotation of the same and the

pinions carried thereby in either direction. Connecting the bars 49 with the adjacent end of the conveyor frame 41 is a pair of bars 57 and the same are adjustable by means of a series of openings 58 being formed therein for selective engagement with the securing pins 59 connecting them to the bars 49, and this adjustment is to be made correspondingly with the adjustment of the brace bars 47 at their points of connection 49 with the frame 41, a series of openings 60 being provided in the opposite side bars of the latter frame for the selective engagement therein of the securing pins 48 carried by the bars 47, whereby the angular inclination of the conveyor frame 41 may be varied with respect to the conveyor frame 36.

Extending forwardly of the truck frame 10, to either side of the conveyor frame 36, and pivoted on the outwardly projecting ends of a shaft 61, which is journaled on the transverse center of the latter, is a pair of bars 62 which rigidly connect at their forward ends to the inner ends of the upper portion of an excavator frame or head 63, and inclining downwardly from the opposite ends of the shaft 61, are a second set of bars 64 which are rigidly connected at their forward ends to the lower inner end of the excavator frame or head 63. Journaled transversely of the upper rear portion of the digger frame or head 63 is a shaft 65, from which is dependingly supported a series of links 66, which pivotally connect as at 67, the rear ends of a series of forwardly extending supporting arms 68, on each of which are carried a series of excavating or digger elements 69, 71, either in the form of toothed blades as shown in Fig. 9, or of shovel blades or scrapers 71, as shown in Fig. 10, depending upon the character of the material to be loaded. However, it is contemplated to have the forward outer excavating elements of the toothed or forked form of the same, as indicated at 69, and the inner of these elements in the form of the shovel or scrapers, as indicated at 71, whereby the blades 69 effect an excavating and loosening action on the material to be loaded, and the blades 71 a feeding action of the loose material inwardly of the head or frame 63 and onto the lower end of the conveyor belt 39. Journaled transversely of the lower forward end of the excavator frame 63 is a crank shaft 72, and on each of the crank arms 73 thereof is journaled one of the excavating arms 68. The several crank arms 73 being offset one equidistantly from the other correspondingly for the number of excavator arms used, or, as shown, 90° apart for the four supporting arms 68 employed in the present instance. For varying the angular relation of the excavator frame 63 with respect to the conveyor frame 36, and correspondingly with the angular adjust- 130

ment of the latter with respect to the truck frame 10, a superstructure 74 is provided on the upper part of the excavator head or frame 63 and from the transverse bar 75 thereof, a pair of flexible elements or cables 76 are extended rearwardly of the excavator head or frame 63 and are wound on a shaft 77 journaled in brackets 78 disposed at opposite sides of the conveyor frame 36, and on 10 one of the projected ends of this shaft 77 is provided a hand crank 79 for rotating the same for the raising and lowering movements of the excavator frame, a ratchet 80 being also provided on the shaft end and 15 having a spring tensioned pawl 81 pivoted on the frame 36 for cooperation therewith to prevent retrograde movement of the shaft 77, after the excavator frame 63 has been properly adjusted. Depending from and 20 extensive with the opposite sides of the excavator frame 63 are a pair of side plates 82, which are pivoted to the latter, as at 83, at the forward end thereof, and these plates are each provided with arcuate slotways 84 25 and 85 engaged over the crank shaft 72 and the bolt 86, respectively, carried by the excavator head or frame 63, and this arrangement allows for free movement of the plates correspondingly with the action of the excavating element 69 with respect to the 30 material being dug or loosened for loading purposes, and also correspondingly for adjustments of the excavator mechanism as a whole. Inclining upwardly from the rear 35 ends of the plates 82 are a pair of bars 87 which are connected at their upper ends by means of a transversely extending rod 88, between which and an eye 89, on the excavator head or frame 63, is connected a 40 coiled spring 90 normally tending to tension the plates 82 in a downward direction, the bars 87 being pivoted to the upper digger frame support bars 62, as at 91, for such purpose. Referring to Fig. 7, it is to be 45 here noted that the supporting arms 68 are each made up of a pair of spaced parallel members 68', and that the excavating elements 69 and 71 are formed with shank portions 69' and 71', respectively which are 50 fitted between the members 68', and are bolted in position therebetween as shown.

For applying power from the driven shaft 26 on the truck frame 10, to the conveyor and excavator mechanisms, the same is provided 55 at its opposite ends with sprockets 92 which are connected by sprocket chains 93 to complementary sprockets 94 carried on the opposite ends of the shaft 61, which is carried medially of the conveyor frame 36, as hereinbefore stated. Keyed on one end of the shaft 61, is a beveled gear 95, which is arranged in mesh with a beveled gear 96 carried on the shaft 97 journaled in brackets 98 along the side of the conveyor frame 36, a 60 beveled gear 99 being carried at the other

end of this shaft 97, and arranged in mesh with a beveled gear 100, the latter being carried on the adjacent end of the roller shaft 38 at the upper end of the conveyor frame 36, whereby the conveyor belt 39 is driven. 70 Keyed on the opposite end of the roller shaft 38 is a sprocket 101 which is connected, by means of a sprocket chain 102, to a sprocket 103, keyed on the adjacent end of the roller shaft 42, upon the rotation of which the conveyor belt 44 is driven in a direction correspondingly to that of the conveyor belt 39, and in a manner to discharge material from the latter outwardly of the rear end of the conveyor frame 41 and at a distance in rear 80 of the rear end of the truck frame 10. At the opposite end of the shaft 61 to that on which the beveled gear 95 is keyed, is mounted a sprocket 104 which is connected, by means of a sprocket chain 105, to a sprocket 85 106 carried at one end of the crank shaft 72 on the digger head or frame 63.

In the operation of the loading apparatus or machine, thus provided for, upon the starting up of the engine or motor 32, and 90 throwing in the clutch mechanism 22, the traction wheels of the rear truck 12 will be driven for the desired forward travel of the machine to and from the loading point, or during the loading operation, as for keeping 95 the digger head well over the material to be loaded. By throwing in the clutch mechanism 28, the conveyor belts 39 and 44 will be driven, and also the supporting arms 68, the latter being reciprocated vertically within 100 the excavator head or frame 63, the blade 69 acting to chop downwardly to loosen the material to be loaded and throwing the loosened material inwardly of the head or frame 63, between the side plates 82, where the 105 rearwardly disposed of the blades 71 will also function to draw and throw the material from the forward blade further backward of the head or frame 63, and onto a flexible foot piece or ground plate 107, carried at the extreme lower end of the conveyor frame 36, which plate 107 is at all times firmly pressed against the ground surface, except, when the machine is travelling from one point to another. It is to be here 110 noted that this foot piece or ground plate 107 extends well within the rear end of the excavator head or frame 63, and under the hindermost blade of the supporting arm, which are inoperative for the actual excavating of the material, and also the side plates 40 of the conveyor frame 36 extend for a distance alongside of the foot piece or ground plate for directing the material upward of the conveyor belt 39. As fast as the 115 material is shoved onto the foot piece 107, it is caught up by the conveyor belt 39 and is carried upwardly of the frame 36, and passed from the upper end thereof onto the conveyor belt 44, which carries it to the rear conveyor 120 125 130

belt 44 which carries it to the end of the conveyor frame 41, and discharges the material rearwardly thereof, where it may be deposited into any desired form of receptacle, wagon, car or the like.

It is well understood that, while the apparatus or machine has been described and illustrated in specific terms and detail, various modifications of the same, changes in the 10 forms and sizes of the parts thereof, the substitution of mechanical equivalent one for the other, may be resorted to without departing from the spirit of the invention, or the scope of the claims appended hereto.

15 Having thus fully described the invention, what is claimed is:—

1. In an apparatus for the purpose set forth, a self-propelled truck, an excavating mechanism suspended forwardly of and from one end of said truck and including excavating and shoveling elements to excavate and shovel rearwardly the excavated material, an elevating conveying mechanism mounted on the forward end of said truck 25 and projecting rearwardly from below the rear of said mechanism for receiving material therefrom, a loading conveyor projecting rearwardly from the rear end of the said elevating mechanism, means for propelling the truck, operative drive connections between said means and said mechanisms, and means for adjusting said excavating mechanism in a vertical direction, and means for adjusting said elevating conveyor mechanism 30 at angle inclinations with respect to said excavator mechanism and truck.

2. In an apparatus for the purpose set forth, a self-propelled truck, an excavating mechanism suspended forwardly of and from one end of said truck and including excavating and shoveling elements to excavate and shovel rearwardly the excavated material, and elevating conveying mechanism mounted on the forward end of said truck and projecting rearwardly from below the rear of said mechanism for receiving material therefrom, a loading conveyor projecting rearwardly from the rear end of the said elevating mechanism, means for propelling the truck, 45 operative drive connections between said means and said mechanisms, and means for adjusting said excavating mechanism in a vertical direction, and means for adjusting said elevating conveyor mechanism at angle 50 inclinations with respect to said excavator mechanism and truck, and means for adjusting said loading conveyor angularly with respect to said conveyor mechanism.

3. In an apparatus for the purpose set forth, a portable truck, driving means therefor mounted thereon, a power distributing shaft journaled transversely of the truck and operatively connected with said driving means, means for transmitting power from

said shaft for driving the truck, an excavator mechanism suspended forwardly of and from one end of the truck and including excavating and shoveling elements to excavate and shovel rearwardly the material excavated, a conveyor pivotally supported on the forward end of the truck, extending rearwardly and upwardly at an inclination and having the forward end thereof positioned under the rear of said mechanism for receiving the material excavated, a loading conveyor having one end extended below said elevating conveyor, extending rearwardly thereof and adapted to receive material therefrom to be loaded, and means for transmitting power from said shaft to said excavator means and said elevating and lowering conveyor.

4. An apparatus for the purpose set forth, comprising a portable truck, an excavator frame suspended forwardly of and from one end of said truck, pivoted supporting arms extending longitudinally of said frame and arranged in parallelism, links depending from and pivoted to said frame and pivotally connected to the rear ends of said arms, a crank shaft extending transversely of said frame forwardly thereof and having the cranks thereof connected to said supporting arms, excavating elements carried at the forward ends of said arms, shoveling elements supported by said arms rearwardly of the excavating elements, a conveyor mechanism extended from said excavator frame and over and mounted on said truck, a loading conveyor projecting rearwardly from said conveyor mechanism, and operating means for the truck, said operating means being operably connected with said supporting arms and said conveyor mechanism and loading conveyor for operating them.

5. In an apparatus for the purpose set forth, a portable truck, excavating elements arranged forwardly of the truck, shoveling elements arranged forwardly of the truck and at the rear of the excavating elements for shoveling rearwardly the material excavated, means for suspending said elements from said truck, a conveyor mechanism supported by the truck and having its forward ends provided with a foot piece arranged in close proximity with said shoveling elements for receiving the excavated material shoveled thereby, a loading conveyor associated with the said conveyor for receiving material therefrom, driving means carried by the truck for said elements, conveyors and truck, means extended from the truck for adjusting said elements, and means mounted on the truck for adjusting said conveying and said loading conveyor.

In testimony whereof, I affix my signature hereto.

FRED L. CAYE.
